UNITED STATES PATENT OFFICE.

HUBERT VAN BREE, OF RACINE, WISCONSIN, ASSIGNOR TO RACINE ELECTRIC COMPANY, OF RACINE, WISCONSIN, A CORPORATION OF WISCONSIN.

CLIPPER.

Application filed May 14, 1923. Serial No. 638,894.

The invention relates to motor-driven hair clippers.

One of the objects of the invention is to provide a motor-driven hair clipper in which 5 the clipper-actuating mechanism is directly connected to the driving motor without the use of a flexible shaft, and which permits the ready disconnection of the clipper from the motor so that different forms of clippers 10 may be readily connected to and used with the same motor, and more particularly the connection between the motor and the clipper includes a separable gear drive connection.

A further object of the invention is to provide a simple and extremely compact clipper 15 drive construction.

The invention further consists in the several features hereinafter set forth and more particularly pointed out by claims at the conclusion hereof.

In the drawings: Fig. 1 is a plan view of a device embodying the invention, with parts removed to show the drive mechanism; Fig. 2 is a side view of the device, parts being 25 broken away and parts being shown in section; Fig. 3 is a section taken on the line 3—3 of Fig. 1.

Referring to the drawings, the numeral 4 designates generally a small electric motor 30 having a casing 4' and an armature or drive shaft 5. A worm 6 is mounted on or may be formed integral with the shaft 5.

The clipper includes a casing or housing 7 having a hollow interior 8 and a cover plate 35 9 resting upon marginal edge flanges 10 of said housing. At its rear end the housing is provided with a bore 11 through which the front bearing 12 for the motor shaft 5 projects, said bearing being on the front end wall 40 13 of the motor housing. This construction permits the shaft and its worm to be properly aligned with the other parts, hereinafter described, in the casing 7. The casing 7 is provided with an end wall or end flange 14 which 45 abuts against the end wall 13 of the motor housing and is secured thereto by screws 15. To provide for quick detachment the end wall 14 of the clipper casing 7 is provided with holes 16 admitting the heads of the screws 50 and slots 17 communicating with said holes so that a partial withdrawal of the screws 15 permits the clipper to be turned for alining the screws 15 with the holes 16 in order that the clipper may be separated from the motor. 55 The heads of the screws 15 are preferably

countersunk to confine them in definite positions in the slots against shifting.

The casing 7 preferably has straight flat top and bottom portions substantially parallel to each other. The front end 18 of the 60 casing 7 is inclined, and to this inclined face a fixed clipper blade 19 is secured by screws 20. This form of connection insures a rigid mounting of the blade on the casing and permits of a handhold close to the blade, thus 65 securing efficient control of the clipper.

A movable blade 21 cooperates with the blade 19 to perform the cutting operation. This blade 21 has a bearing surface running on the upper surface of the blade 19 and is 70 guided in its movement with respect to the blade 21 by tongues 22 running in a transverse slot or groove 23 in said blade 19. The blade 21 is retained in operative position against the blade 19 by a compression plate 75 24 mounted on the housing and having its forward edge portion 25 yieldingly maintained against the movable blade by means of a spring 26 mounted on a stud or post 27 carried by the casing, said spring being interposed between said plate and an adjustable thumb nut 28 on the upper threaded end of said stud so that the pressure exerted by the plate upon the blade may be varied as desired. The compression plate 24 has ears or flanges 80 29 fitting over the sides of the casing to hold it against lateral movement.

The post or stud 27 is alined with the axis of the shaft 6 and centered in a slot 30 in the front end of the casing. A flat rocking lever 90 31 is pivotally mounted intermediate its ends upon the stud or post 27 and its pivotal portion works in said slot 30 in the front end of the casing 7. One arm 33 of this lever engages the sides of a slot 34 centrally located in the 95 rear edge portion of the blade 21. The other arm 35 of this lever is canted or obliquely inclined from the arm 33 and is provided with a slot 36 in which a driving block 37 is slidably mounted. The block 37 is pivotally mounted on a crank pin 38 carried by a worm-wheel 39. The wheel 39 is journalled on a stud 40 fixedly mounted in the casing 7 at one side of the motor shaft and is adapted to mesh with the worm 6 when the clipper is connected to the motor. The worm may be readily disconnected from the worm-wheel so that interchangeable clippers designed for different depths of cut may be connected to the motor. 100 105 110

The clipper is preferably gripped near the blades when operating it, and the casing of the clipper and that of the motor are made of a light weight metal to facilitate handling 5 the device. The conductor wires 41 for the motor enter the rear end of the motor housing so that they do not interfere with the free movement of the device.

I desire it to be understood that this invention 10 is not limited to any specific form or arrangement of parts except in so far as such limitations are specified in the claims.

What I claim as my invention is:

1. In a motor-driven clipper, the combination 15 of a clipper casing having an end wall including a central aperture, a motor casing having an end wall abutting against said first-named end wall and having a projecting shaft entering said aperture, one of said end walls 20 having a central alining boss fitting within a recess in the other end wall, there being a plurality of slots in one of said end walls disposed substantially arcuately about the axis of said abutting end walls and threaded openings 25 in the other end wall in register with said slots, and headed screws passing through said slots and entering said threaded openings for clamping said end walls in abutment, said slots each having an enlarged end portion for 30 permitting free passage of said headed screws

therethrough after relative rotation of said end walls about their axis, and at least one of said slots having at its other end a countersunk portion receiving the head of the co-operating screw for locking said end walls 35 against relative rotation when said screw is threaded in place.

2. In a motor-driven clipper, the combination of a flat sector-shaped casing divergent rearwardly and having a rear end wall including flange portions projecting at opposite sides from the plane of the casing, said end wall having a central bore communicating with the interior of the casing, clipper blades mounted at the front portion of the casing, 40 clipper actuating mechanism within the casing, an electric motor having a front end wall abutting against the rear end wall of said casing and including a shaft projecting into said casing through said bore and having a 45 detachable operative connection with said actuating mechanism, and fastening means passing through the oppositely projecting end wall flange portions of said clipper casing for releasably securing the end wall of said motor 50 in clamping end abutment with said end wall of said casing.

In testimony whereof, I affix my signature.

HUBERT VAN BREE.
